(57) **CLAIM**

The ornamental design for a lithium battery assembly as shown and described.

DESCRIPTION

FIG. 1 is a top, rear and right side perspective view of a lithium battery assembly showing our new design; FIG. 2 is a bottom, rear and right side perspective view thereof;

FIG. 3 is a top, front and left side perspective view thereof; FIG. 4 is a bottom, front and left side perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof;

FIG. 10 is a bottom plan view thereof;

FIG. 11 is an enlarged view of portion 11 in FIG. 1; and, FIG. 12 is an enlarged view of portion 12 in FIG. 2.

The evenly broken lines in the drawings illustrate portions of the lithium battery assembly which form no part of the claimed design.

The unevenly dashed broken lines illustrate the boundary of the enlarged views and form no part of the claimed design.
